UNITED STATES PATENT OFFICE.

SOREN RINGER, OF CHICAGO, ILLINOIS.

FILE HOLDER.

Application filed June 25, 1920. Serial No. 391,846.

To all whom it may concern:

Be it known that I, SOREN RINGER, a subject of the King of Denmark, residing at Chicago, in the county of Cook and State 5 of Illinois, have invented certain new and useful Improvements in a File Holder, of which the following is a specification.

This invention relates in general to filing devices in which letters, documents, and 10 other files are stored, and has more particular reference to means for holding the files in the drawer in compact and upright position.

One of the primary objects of my present 15 invention is to provide a file holder which will be simple in construction, cheap to manufacture, one which can be quickly adjusted into position to accommodate a greater or less number of files, and one which 20 will be automatically locked in adjusted position.

Other objects and advantages of my invention will be apparent, as the same becomes better understood, by reference to the following description, when considered in connection with the accompanying drawings.

Referring to the drawings:

Fig. 1 is a perspective view partly broken away of a filing drawer equipped with my 25 invention; and

Fig. 2 is a detail view of the file holder and its support.

By reference to the drawings, it will be observed that my invention as shown, is 30 applied to a filing drawer, designated generally by reference character 3, which may be of any well known or preferred construction, the drawer shown for purposes of illustration comprising a front wall 4, side walls 40 5 and 6 respectively, and a bottom 7. This drawer is adapted to contain a block or stack of files 8, which may be letters or other documents, on edge in the drawer.

Letters or other thin sheets of paper will 45 not remain in upright position unless they are held against a wall of the drawer, and my invention aims, primarily, to provide means for holding such files in upright position between one of the side walls 5 of the drawer and a stiff follower 9 of cardboard, or other preferred material.

With this end in view, I equip the rear 50 end of the drawer with a transversely extending rod or support 11, which is attached at each end to the side walls of the drawer. The method of attachment is, of course,

immaterial to the present invention, but preferably, the rear edge of each drawer is provided with an eye or loop, adapted to receive the downturned ends 12 of the rod 60 11, whereby the rod is retained in position and the side walls are locked together.

Upon this rod or support, I mount the holding member proper, designated by reference character 13. This member is made 65 of spring wire curved at its forward end to provide a substantially vertically disposed loop 14 adapted to lie against the face of the follower 9, and at its rear end the member is coiled around the rod 11, as indicated 70 at 15.

It will be observed that the convolutions of the coil or spiral around the rod 11 are quite widely separated one from the other, and the longitudinal axis of this coil is so disposed that it causes the body portion of the member 13 to project at a slight angle to the longitudinal axis of the rod 11, as indicated in full lines in Figure 2. When no lateral pressure is exerted on the member 13, it is freely slideable longitudinally 75

of the rod 11, thus permitting it to be adjusted to accommodate a greater or less number of files in the drawer. When the member is swung in a clockwise direction through an angle of 180° from the position shown in 80 Figure 1, it may be so adjusted on the rod, but when swung back into the operative position shown in Figure 1, it lies closely against the outer face of the follower 9 and is sprung from the full line position shown 85

in Figure 1 to the dotted line position shown therein, thus binding the rod 11 so that the member is locked against movement longitudinally thereof and exerts a lateral pressure upon the follower 9, which clamps the 90 files 8 snugly between this follower and the side wall 5 of the drawer.

When access to any of the files is desired, the member 13 is swung in a clockwise direction into inoperative position, thus releasing the files for inspection or removal, and upon the replacement of the files, the holding member is swung back into the position shown in Figure 1. Should it be desirable to remove the member entirely for replacement or repairs, should the same become necessary, this may be accomplished by swinging the member into inoperative position and then turning it at an angle to the rod 11 so that the coil portion of the member may be disengaged from the rod 110 without bending or distorting the member.

It will be apparent from the foregoing that I have provided a file holder which is simple in construction, cheap to manufacture, and easy to assemble, one which will snugly hold the files under compression, one which can be readily moved from operative to inoperative position and vice versa, and one which, while capable of adjustment to any desired position, will be automatically locked upon its support so as to properly hold the files in position in the drawer to which my invention is applied.

15 While I have shown and described a preferred embodiment of my invention it should be understood that it is capable of considerable modification without departing from the spirit thereof, as defined in the following claims.

I claim:

- 20 1. In a file holder, the combination of a receptacle adapted to contain vertically disposed files, a rod extending transversely of said files at one end thereof, and a file-holding member consisting of a spring wire shaped at one end to provide a relatively

25

large vertically disposed loop adapted to engage the outermost file and provided at its other end with a coil comprising convolutions spaced apart a distance greater than the diameter of said rod and embracing said rod whereby said member is pivotally supported on said rod, said coil being self-locking on the rod under lateral pressure exerted upon the member in one direction and detachable from the rod when angled relatively thereto.

2. In a file holder, the combination of a receptacle adapted to contain vertically disposed files, a rod extending transversely of said receptacle at one end thereof, and a file-holding member consisting of a spring wire coiled at one end to embrace said rod whereby said member is pivotally supported, the convolutions of said coil being spaced apart a sufficient distance to permit detachment of said member from said rod upon movement of said member into a predetermined angular position with respect to the rod. 40 45

SOREN RINGER.
